CLUTCH-TYPE UMBRELLA CARRYING CASE

Heinz Weber, Hilden, Germany, assignor to Telesco Brophy Limited, Montreal, Quebec, Canada

Filed Apr. 28, 1972, Ser. No. 248,785

Claims priority, application Germany Oct. 29, 1971

Term of patent 14 years

Int. Cl. D3—01

U.S. Cl. D87—1 R

FIG. 1

FIG. 4

FIG. 2

FIG. 3

FIG. 5

FIG. 6

FIG. 1 is a perspective view of a clutch-type umbrella carrying case showing my new design, with a portion being broken away for convenience of illustration.

FIG. 2 is a front elevational view;

FIG. 3 is an end elevational view looking from the left of FIG. 2, the right-hand end view being a mirror image thereof;

FIG. 4 is a top plan view;

FIG. 5 is a bottom plan view; and

FIG. 6 is a rear elevational view.

I claim:

The ornamental design for a clutch-type umbrella carrying case, as shown and described.
